(57) **CLAIM**

The ornamental design for a calendar with applied surface pattern, as shown and described.

DESCRIPTION

FIG. 1 is a front perspective view of the calendar with applied surface pattern showing my new design;
FIG. 2 is a rear perspective view thereof;
FIG. 3 is a front thereof;
FIG. 4 is a rear view thereof;
FIG. 5 is a left side view thereof;
FIG. 6 is a right side view thereof;
FIG. 7 is a top view thereof;
FIG. 8 is a bottom view thereof; and,
FIG. 9 is alternate embodiment of the rear perspective view of the calendar with applied surface pattern wherein the rear surface is without the surface pattern.

The broken lines showing the outline of a cross is directed to the environment. The numbers disposed below the solid line letters are illustrated in broken lines. The broken lines for the year indicia at the top of the pattern are for illustration only. None of the broken lines form a part of the claimed design. The surface pattern is not limited to the scale shown herein.
